DISPLAY HOLDER FOR DISPLAYING BOTH SIDES OF A SINGLE COIN

Giorgio I. Spadaro, Evanston, Ill., assignor to
Simon L. Friedman, Chicago, Ill.

Filed July 2, 1962, Ser. No. 70,768

Term of patent 14 years

(Cl. D87—3)

FIGURE 1 is a perspective view of a display holder for displaying both sides of a single coin embodying my new design;

FIGURE 2 is a side elevational view; the side opposite that shown being the same in appearance as the side shown;

FIGURE 3 is a top plan view;

FIGURE 4 is an edge view; and

FIGURE 5 is a bottom plan view thereof.

I claim:

The ornamental design for a display holder for displaying both sides of a single coin, substantially as shown and described.
